UNITED STATES PATENT OFFICE.

FRED ERNEST PAYNE, OF MIDDLETOWN, CONNECTICUT, ASSIGNEE TO GOODYEAR RUBBER COMPANY, OF MIDDLETOWN, CONNECTICUT, A CORPORATION.

ARCTIC OVERSHOE.

1,286,760.

Specification of Letters Patent.

Patented Dec. 3, 1918.

Application filed April 8, 1918. Serial No. 227,204.

To all whom it may concern:

Be it known that I, FRED ERNEST PAYNE, a citizen of the United States, residing at Middletown, in the county of Middlesex and 5 State of Connecticut, have invented certain new and useful Improvements in Arctic Overshoes, of which the following is a specification.

My invention relates to improvements in 10 arctic overshoes, having particular relation to protection of the instep portion against damage due to the rubbing contact of the separable fastener positioned at the instep, and the object of my improvement is to provide a guard in the form of a tongue of suitable form and material that is positioned when in use between the said separable fastener and the body of the shoe to take 15 the wear and at the same time to so construct and arrange the said tongue that the shoe can be fastened readily, being brought from the open and unlocked position to the closed and locked position, without paying particular attention to the tongue, and with 20 the tongue assuming the proper position for providing the protection desired.

In the accompanying drawing:

Figure 1 is a side elevation of an arctic overshoe embodying my invention.

Fig. 2 is a front elevation, on an enlarged scale, of the separable fastener positioned at the instep and the adjacent parts.

Fig. 3 is a side elevation of the catch member of the fastener, in disconnected position, and the adjacent parts, showing the protecting tongue at the rear of the said catch member.

Fig. 4 is a rear elevation of the same.

Fig. 5 is a plan view of the blank for the 40 protecting tongue.

The structure of the shoe 10 generally to which my invention applies is that of the arctic overshoe of well known form, comprising a leg portion extending upwardly from the foot portion 12, and having as one feature of the construction a pair of side flaps 13, one on each side, extending upwardly along the leg portion 11. The front edges of the flaps 13 are opposed one to the other along the front of the leg portion 11 but do not quite meet and the front edge portions are secured together by a plurality of adjustable separable fasteners 14 distributed along the said front edge portions, the lowermost fastener 14 being positioned

adjacent the upper part of the instep 15 or, as may be designated, at the junction 16 of the instep 15 and the leg portion 11 at the front part of the shoe structure.

Thus the said lowermost fastener 14 is positioned where there is a relatively abrupt change in shape of the shoe structure, as the upper wall of the instep 15 is appreciably inclined and the front wall 17 of the leg portion is more nearly vertical and may even be inclined slightly in the reverse direction than the said upper wall of the instep 15. Therefore, the formation at the said junction 16 is in the form of a relatively sharp turn, involving an abrupt change, as 60 mentioned, and in some cases, according to the securing positions of the fasteners used by the wearer, may assume the form of a sharp angle, and with the said lowermost fastener 14 positioned at the apex portion. 65

As a matter of practicable observation I have noted that the said lower fastener 14, which may be designated as the instep fastener, is subjected to an appreciably greater strain than the fasteners 14 positioned above 70 the same, along the leg portion 11. So much so, in fact, that the particular portion 16 of the shoe structure 10 that is opposed thereto becomes worn excessively compared to the other parts of the shoe, and generally is the 75 part that wears out first, being worn through before the other parts of the shoe are badly worn.

My invention overcomes the condition described.

The material of which the body of the shoe 10 is made is rubber, faced on the outer side with fabric and also lined with fabric. This detail may be changed if desired.

The separable fastener 14 is composed of 80 a keeper 18, which in the shoe 10 shown is secured to the flap 13 on the left side, and a catch member 19, secured to the right flap 13, the securing means in each case being in the form of a loop of suitable fabric, designated in the factory by the shop term frication.

The keeper 18 has a set of slots 21 for providing a choice of effective length for purpose of adjustment for receiving the 105 spring positioned hook 22 of the catch member 19.

In order to take the wear of the instep fastener 14 I interpose between the same and the opposed portion 16 of the shoe 10 110

a layer 23 of suitable material and which, in order to meet certain conditions other than simply wear I construct and arrange in a special manner.

5 Thus the material itself has a body 24, which is exposed at the back, as shown in Fig. 4, and is faced at the front with fabric 25, as shown in Fig. 2, to correspond to the fabric 26 of the body of the shoe 10. This 10 construction provides a stiffness that is desirable for positioning the device in what may be designated the ready to use position.

For it is desirable that the device will readily assume the proper position for use 15 as the flaps are brought to the closed position, without special attention on the part of the wearer, so that, in fact, he has no more parts to handle or look out for than before the device described was incorporated 20 in the shoe.

As further details for effecting the result referred to I provide the protecting layer 23 in the form of a tongue that is secured to the right flap 13 and extends outwardly 25 therefrom, below the catch member 19, and is secured to the said flap 13 by means of a securing portion 27 of appreciable length. As a further detail, the securing portion 27 is turned inwardly or folded over along 30 the edges 28 for the portion opposed to and secured to the flap 13 and just outside the edge 30 of the flap 13 there is a portion 31 where the folded edges 28 open outwardly abruptly to the full width of the tongue 35 24. Thus the portion 31 described has stiffened edge portions which merge on the inner side with the folded edge 28 of the supporting or securing portion 27 and which merge on the outer side with the edge of the tongue 40 24, being of double thickness on the one side and single thickness on the other side, and of double thickness intermediate the two sides in the form of a turned edge, with the turn being made along an oblique line.

Thus the portion 31 is adapted to serve 45 as a shank that is relatively stiff or rigid, with reinforced edges, suitable to tend to position the tongue 24 in a definite position and as incorporated in the structure of the shoe 10 the device is positioned so that the 50 tongue will be swung essentially into proper position under the fastener as the flap to which it is connected is moved over to the closed position.

The special construction and arrangement 55 of the protecting tongue described obviates the tendency of the tongue to turn inwardly and double under, so as to be in the way and a cause of annoyance instead of helpful and useful device, and the provision of the 60 said device I find adds materially to the useful life of the shoe.

I claim as my invention:

1. An arctic overshoe having a pair of side flaps that close over against the instep portion and having a pair of mating fastening members that are mounted on the said flaps and interengage across the said instep portion, and a protecting tongue positioned under the said members and secured by one 70 end to one of the said flaps.

2. In an arctic overshoe, a side flap having a fastening member projecting outwardly from the edge portion, a protecting device in the form of a tongue positioned on the 75 inner side of the said fastening member and having a supporting portion at one end that is secured to the said edge portion, the said tongue being made of composite material, comprising a body of rubber faced 80 with fabric, and the two lateral edge portions of the said tongue, on opposite sides, for the part of the tongue that extends across the junction of the tongue with the said edge portion of the side flap being turned over 85 for effecting a stiffening of the said part.

FRED ERNEST PAYNE.
